UNITED STATES PATENT OFFICE.

JOSEPH A. HALLS, OF YOUNGSTOWN, OHIO, ASSIGNOR TO THE GENERAL FIREPROOFING COMPANY, OF YOUNGSTOWN, OHIO, A CORPORATION OF OHIO.

DIE FOR METAL-EXPANDING MACHINES.

Application filed August 30, 1922. Serial No. 585,248.

To all whom it may concern:

Be it known that I, JOSEPH A. HALLS, citizen of the United States, residing at Youngstown, in the county of Mahoning and State 5 of Ohio, have invented certain new and useful Improvements in Dies for Metal-Expanding Machines, of which the following is a specification.

This invention relates to metal expanding 10 machines, and more particularly to an improvement in the means for opening the slotted sheet into meshes.

To that end the invention contemplates a 15 novel expanding die that provides a greater bearing surface against the die block and also has features of construction which practically double its life as compared with the ordinary single die, and yet at the same time involves little additional cost for fabrication, besides obviating wastage of metal.

A further object of the invention is to 20 provide an expanding unit for opening the strands of the slotted sheets into meshes which consists of the novel die above referred to and a suitable deflector disc cooperating therewith.

With the above and other objects in view 25 which will more readily appear as the nature of the invention is better understood, the same consists in the novel construction, combination and arrangement of parts hereinafter more fully described, illustrated and claimed.

A preferred and practical embodiment of 30 the invention is shown in the accompanying drawings, in which:

Figure 1 is a vertical cross sectional view 35 of a portion of the machine embodying the invention.

Figure 2 is a top plan view of the portion 40 of the machine showing several of the expander units.

Figure 3 is a detail plan view of one of 45 the improved dies.

Figure 4 is an end view thereof.

Figure 5 is an edge view of the die shown 50 in Figure 3.

Similar reference characters designate corresponding parts throughout the several figures of the drawings.

As previously indicated, the novel and distinctive feature of the present invention is that of a special die construction for co-

operating with deflecting means to provide an expanding unit for opening the strands 55 of the slotted sheet into meshes, the die being designated generally as A and the deflecting disc designated as B.

As will be observed from the drawings, more particularly Figures 3, 4 and 5, the 60 said die A consists of a body 1 provided on one face thereof and at the opposite ends 2 with a series of steps or shoulders 3 extending obliquely thereof, thereby providing duplicate sets of inclined shoulders at opposite 65 ends of the die.

By providing the opposite ends of the die 70 with the duplicate steps or shoulders, the important advantage of providing a reversible die is obtained which makes it possible 75 to use the same die by reversing it end for end with its former position, thereby to bring the unused shouldered portion of the die into use when the other part of the die has become worn or otherwise unfit for further use. This novel arrangement not only 80 has the advantage of increasing the life of the die as above explained but also does not require the use of much more metal than a single die consequently making it possible to 85 provide, in effect, two dies at the cost of one.

The intermediate portion of the die body 1 is provided with the elongated openings 4 for receiving fastening screws 5 for securing the die to the die block 6 of the machine. Obviously, by reason of the elongated openings 4, it is possible to adjust 90 the die on the die block within the desired limits so as to seat the same accurately with reference to dies of adjacent expanding units, accuracy of alinement of the dies being essential to continuous operation 95 of the machine and a perfect product.

As shown in Figures 1 and 2, the deflector disk B overlies the stepped end of 100 the die A so as to positively deflect the strands of the slotted metal sheet against the shoulders 3 of the die. This deflector disk B may be carried by the knurled feeding roller 7 which cooperates with a correspondingly knurled feed roller 8, nested 105 in the die block, to feed the slotted metal sheet through the machine and against the deflector disk B which directs and bends the slotted metal sheet over and against the shoulders 3 of the die A, so that, as the

sheet is continuously fed or propelled by rollers 7 and 8 through the pass formed thereby the previously slitted strands of the blank will be opened into meshes to form a 5 diamond-mesh expanded metal fabric.

Although the present improvement may be adapted for use on various types of machines, nevertheless, for illustrative purposes the said rollers 7 and 8 may be carried upon the shafts s and s' , the latter being the drive shaft because it has associated therewith the bevel drive gear s^2 which is driven by the relatively large driving gear s^3 .

15 The driving gear s^3 , as well as the other associated parts of the apparatus, are similar to and perform the general functions of the metal expanding machine illustrated in the patent to H. E. White, No. 1,061,953 dated May 13, 1913.

From the foregoing it is thought that the features and advantages of the improvement will be readily apparent to those skilled in the art.

20 25 I claim:

1. A die for metal expanding apparatus comprising a body having on one face thereof and at each side of its transverse center a plurality of obliquely extending shoulders, said shoulders facing outwardly at opposite ends of the die.

30 35 2. In a metal expanding apparatus, an expanding unit comprising a reversible die having oblique shoulders and deflecting

means for moving the strands of the fabric 35 into engagement with said shoulders.

3. In a metal expanding apparatus, an expanding unit comprising a reversible die having duplicate sets of inclined shoulders, and deflecting means for moving the strands 40 of the fabric into engagement with said shoulders.

4. In a metal expanding apparatus, an expanding unit comprising a reversible die having duplicate sets of inclined shoulders, 45 and a deflector disc for moving the strands of the fabric into engagement with said shoulders.

5. In a metal expanding apparatus, an expanding unit comprising a reversible die having duplicate sets of inclined shoulders, 50 and a rotary deflecting disc for moving the strands of the fabric into engagement with said shoulders.

6. In a metal expanding apparatus, an expanding unit comprising a reversible die having duplicate sets of inclined shoulders and a rotary deflecting disc overlying said inclined shoulders and adapted to move the strands of the fabric into engagement there- 55 with.

In testimony whereof I hereunto affix my signature in the presence of two witnesses.

JOSEPH A. HALLS.
